UNITED STATES PATENT OFFICE.

BRADLEY L. BENSON, OF SAN FRANCISCO, CALIFORNIA.

METHOD OF AND MACHINE FOR SPACING TILES AND PASTING SAME TO PAPER.

1,404,567.

Specification of Letters Patent. Patented Jan. 24, 1922.

Application filed January 27, 1921. Serial No. 440,322.

To all whom it may concern:

Be it known that I, BRADLEY L. BENSON, a citizen of the United States of America, residing at San Francisco, in the county of 5 San Francisco and State of California, have invented certain new and useful Improvements in Methods of and Machines for Spacing Tiles and Pasting Same to Paper, of which the following is a specification.

10 This invention is an improved method of and machine for spacing tiles for pasting same to paper.

Attention is called to my co-pending application Serial Number 383,978, filed May 15 24th, 1920.

20 The primary object of the present invention is to provide a positive means for filling a rectangular space with a given number of tiles in spaced relation to each other and pasting same to a sheet, irrespective of any variation in size of the individual tiles.

In the co-pending application before mentioned I depended on the curvature of a surface to space the tiles in one direction. In 25 practice I find that tiles coming from the kilns vary in size, due to the difference in kiln temperatures and other causes, and that when spaced on a curved surface, the length of the various courses are at variance. Obviously this would seriously impede the tile 30 setter in attempting to match the edge of one pasted sheet with that of the next.

The present method and machine will position and space tiles in courses of even length 35 and the edges of the pasted sheets will match.

In this specification and the annexed drawings, the invention is illustrated in the form considered to be the best, but it is 40 understood that the invention is not limited to such form, because it may be embodied in other forms and it is also to be understood that in and by claims following the description it is desired to cover the invention 45 in whatever form it may be embodied.

In the accompanying two sheets of drawings, Fig. 1 is a vertical central section of my machine.

Fig. 2 is a top plan view of the same. 50 Fig. 3 is an enlarged fragmentary view of a wheel, partly in section, illustrating the method of spacing.

Fig. 4 is a fragmentary plan view of the 55 periphery of a spacing wheel adapted for use with square tile.

Fig. 5 is a similar view of a spacing wheel for what is termed "broken joint squares" in which the courses are in staggered relation to each other.

Fig. 6 is a fragmentary plan view of the 60 periphery of a spacing wheel arranged for hexagonal tile.

Fig. 7 is a fragmentary detail in perspective illustrating a modification of the feed device for the spacing wheel made necessary by the hexagonal shape of tile. 65

Fig. 8 is a diagrammatic view showing how my method may be carried out by using pasting boards instead of the continuous spacing wheel. 70

Fig. 9 is a cross section view of a wiper bar.

Referring to the drawings, Fig. 1, the numeral 1 designates one of the side sills of the frame of my machine. 75

Similar side members 2 are directly above and connected thereto by corner pieces 3 and by vertical standards 4 which extend above the member 2 and are provided with a series of notches 6 to engage a bar 7. 80

The members 1 and 2 are also connected by side members 8, but one of which is shown here.

The frame work is held together at suitable intervals by cross members such as 85 5 and 10.

Journalled in the side members 8 is an axle 9 on which is rotatably mounted on a spacing wheel 11 which may be manually rotated or driven by suitable power. The 90 wheel 11 is provided with a number of upstanding spacers 12 which extend radially therefrom at regular intervals on the periphery.

These spacers 12 are preferably of a 95 height less than that of the tile to be spaced.

At 13, 14, Figs. 1 and 2, I show flat plates secured at one end to the side members 2 by screws 16. The opposite ends of members 13 and 14 are turned back to form bearings 100 for pins 17 and 18 extending outwardly from the sides of the lower end of a chute 19 which is divided into a plurality of grooves or courses by upstanding spacers 21.

This chute 19 is adapted to convey tiles 105 to be pasted and deliver same to the periphery of the wheel 11.

The lower end of said chute may be raised or lowered in relation to said wheel by adjusting set screws 22, 23 which are threaded 110

in the members 13 and 14 and bear against the side members 2.

The angle of inclination of the chute 19 may be adjusted by moving rod 7 to another of the notches 6.

The chute 19 is in secant relation to the periphery of the wheel 11. The reason for this is shown more clearly in Fig. 3. As the tiles in the courses of chute 19 gravitate to the bottom the leading tile encounters the periphery of wheel 11 and the weight of those behind force it forward until it encounters a spacer 12. This action is repeated for each tile, but it will be noted in Fig. 3 that the tile marked "A," while still being pressed by the tile B and the combined weight of those in the chute 19, has been forced to a flat position on the periphery of the wheel and thus an angle is formed between tile A and tile B sufficient to allow the next advancing spacer 12 to enter between said tiles as the wheel 11 is rotated. By this means the tiles successively advance from the chute 19 and are crowded against the spacers 12 and assume positions shown at C, D and E.

The distance between the spacers 12 is slightly greater than the length of the tiles and any inequality of size is accommodated thereby.

The tiles are carried around the wheel 11 to a point where gravity might disturb them and here an endless flexible belt 21 is provided against a portion of the periphery of the wheel during rotation.

The belt 21 passes around rollers 22, 23 and 24.

A pasted sheet 26 is fed in by any suitable feed or gripper device and applied to the tiles. The band 21 being elastic insures contact between the pasted sheet 26 and the tiles.

As the wheel 11 rotates the sheet encounters a plate 27 and the weight of the tile causes the sheet to fall away from the wheel and onto the plate 27.

The elastic belt and delivery means are fully described and claimed in another application before mentioned.

In order to prevent any clogging or tendency on the part of the tile to climb out of the chute 19 at the delivery end, I provide an idler wheel 26 for each course of tile in said chute.

At 27 and 28 I show bearing blocks secured to the sides of the chute 19 by screws 29.

Extending across the chute 19 and above same are two rods 31 and 32 secured at the ends to the bearing blocks 27, 28.

The purpose of these rods is best shown in Fig. 3. Each of the idler wheels 26 must be free to rise and fall independently of the others as any interruption in one course

of moving tiles will not affect the other courses.

Each of the idlers 26 is rotatably mounted on an L shaped wire 33 which is coiled at the end remote from the idler to form a bearing on the rod 31. The wires 33 rest normally on the rod 32 and are yieldably held in that position by springs 35 coiled about the rod 32 and bearing at each end against the wires 33 at opposite sides of the rod 32. This arrangement allows any of the idler wheels 26 to rise slightly to accommodate thicker or higher tiles and the freely rotating idlers serve to hold the courses down at the point where the plane of travel is broken with the minimum amount of friction.

Should a tile fail to pocket as described the flow can be continued and interruption avoided by using drag or follower bar shown at 34 rigidly secured to arms 36 and 37 which are pivotally connected to the rod 17.

This bar is shown in Fig. 9 in cross section. It is cut away at 38 to permit entrance under the idlers 26 and is rounded at the under edge as shown at 39 to offer a yielding resistance to any incoming tile which is out of place. The weight of the bar causes the tile in the advancing course to stop until the next advancing spacer 12 reaches the advance edge of the misplaced tile when the same will drop into place and the operation again becomes normal.

In Figs. 1 and 2 I have shown the spacers 12 extending transversely across the periphery of the wheel 11.

If desired cross spacers 41, Fig. 4 may be used.

In Fig. 5 I show these cross spacers 41 staggered to paste tile in broken joints.

In Fig. 6 I show spacers 42 arranged on the periphery of the wheel 11 for hexagon tiles. I find that these may be fed and pasted in the manner herein described for square tiles if the chute 19 is modified.

It will be seen that the courses around the periphery of the wheel 11 is zigzag as indicated at the arrows in Fig. 6. As each course is fed down the incline in a separate chute these chutes must overlap each other on the lines that interlock as indicated by the arrows in Fig. 6.

I have found that if the chutes for feeding hexagonal tile are placed as shown in Fig. 7, so that the alternate courses approach the wheel 11 at different angles, the said tiles will feed into place in the pockets formed by spacers 42 in the manner heretofore described.

This has the effect of laying alternate courses on said wheel and later filling in between said courses to form a solid sheet.

Obviously my invention might be em-

ployed as shown in Fig. 8, in which the chutes 19 empty into flat boards 44 which are conducted beneath the delivery end of said chutes on an endless belt 46 around 5 rollers 47 and 48.

I prefer to use the rotary device for speed and efficiency.

I claim:

1. The method of spacing tiles consisting 10 of conducting said tiles in processions through chutes inclined toward and adapted to empty into a member having raised spacers thereon adapted to form pockets of greater area than that of each of said tiles 15 in such a manner that the weight of the processions in said chutes will force all of said tiles into said pockets and against the sides of the pockets that are remote from said chutes.

20 2. An apparatus for spacing tiles for pasting comprising a series of inclined chutes, a member adapted to be moved past the discharge end of said chutes and provided with pockets each of greater area than that of 25 each of said tiles, the said pockets being arranged to register with and be fed by said chutes during movement.

3. An apparatus for spacing tiles for pasting comprising a frame, a spacing wheel 30 revolvably mounted in said frame and provided with raised spacers on the periphery thereof, a plurality of chutes adapted to convey tiles in courses and discharge same on the periphery of the wheel at an angle 35 secant to said periphery.

4. An apparatus for placing a given number of tiles in a given area in spaced relation to each other, comprising a plurality of chutes adapted to convey loose tiles there-

through by gravity, a member provided 40 with raised spacers adapted to be moved under the discharge end of said chutes and withdraw the tiles therefrom individually in such a manner that the tiles will be successively forced against said raised spacers 45 by the weight of the advancing tiles in said chute.

5. A machine for spacing tiles for pasting comprising a movable member provided with upstanding spacers thereon, inclined 50 chutes adapted to discharge tiles in courses onto said movable member at an angle thereto, means near the angle of intersection of the said chute with the said movable member for maintaining an even flow of courses 55 of tile from said chute to said movable member.

6. A machine for spacing tiles for pasting comprising a movable member provided with upstanding spacers thereon, inclined 60 chutes adapted to discharge tiles in courses onto said movable member at an angle thereto, means near the angle of intersection of said chute with the said movable member for maintaining an even flow of courses of 65 tile from said chute to said movable member, said means comprising an idler wheel for each of said courses yieldably and rotatably mounted above said tile adjacent the delivery end of said chute. 70

7. The method of spacing tiles for pasting which consists in withdrawing the said tiles successively from inclined chutes to a spacing member arranged at an intersecting angle which will spread the tiles apart to 75 successively admit spacing elements.

In testimony whereof, I affix my signature.
BRADLEY L. BENSON.
